STOKER PUSHER BAR

John S. Skelly, Monongahela, Pa., assignor to
Combustion Engineering Company, Inc., New
York, N. Y.

Application March 12, 1945, Serial No. 582,311

2 Claims. (Cl. 110—44)

1

This invention relates to stokers for fuels and particularly to improvements in the retort type of stoker.

In one form of retort stoker, the fuel is advanced through the retort by pushers comprising wedge-shaped blocks having a steep inclined face extending upwardly in the retort on the side of the blocks facing the direction of the fuel movement and a flat inclined face sloping upwardly toward the steep face on the side of the blocks facing in the opposite direction. These blocks are usually mounted on a bar which slides on the bottom of the retort and is moved back and forth by driving means, thereby reciprocating the pushers and causing the fuel to be advanced through the retort. It has been found that during operation, the fuel works into the space between the bar and the bottom of the retort, packs there and exerts an upward pressure on the bar tending to lift it. This pressure is resisted by the bearings for the bar at the ends of the retort thereby increasing the pressure thereon and tends to bend the bar upwardly. This results in an increase in bar friction and bearing wear and consequently of the power to drive the stoker.

It is an object of this invention to provide an improved pusher bar which will overcome the above objections.

Figure 1 is a longitudinal sectional view through a retort of a stoker embodying the improved bar.

Figure 2 is a transverse section through the retort and improved bar taken on line 2—2 in Figure 1;

Figure 3 is a top plan view of the improved bar; and

Figure 4 is a bottom view of the improved bar.

The stoker illustrated comprises a retort 10 to which coal is fed from a hopper 11 by means of a screw 12, and containing a movable pusher bar 13 having auxiliary distributors, agitators or pushers 14 thereon arranged to advance and distribute the coal uniformly over the retort area and to agitate the fire bed. The retort, as shown in Fig. 2, is substantially U-shaped in transverse section and its rearward end is closed by means of an upwardly inclined wall 19 while its forward end terminates in a tubular portion adjacent the housing for screw 12.

An air chamber 15 surrounds the retort and in order that air for combustion may be directed into and across the top of the retort where combustion takes place, a tuyère 16 bridges the space between the side and end walls of the re-

2

tort and air chamber and is supported thereon.

As mentioned the fuel to be fed to the retort 10 is stored in hopper 11 having an open bottom which is disposed over a housing 17 in which the forward end of the feed screw 12 operates. The feed screw lies in the bottom of the housing and is mounted in a bearing 18 secured in the rear wall 20 thereof. The opposite wall of housing 17 has an opening 21 through which screw 12 projects into the feed screw housing. As shown, the feed screw housing is secured to housing 17 and to end wall 22 of the air chamber 15 so that it will be held in the proper operating position and in alignment throughout its full length.

Since the feed screw is driven at a relatively low speed, one or two revolutions per minute for example, the screw is driven from motor 23 through a speed reducer or gear reduction mechanism 24 of any standard design suitable for the purpose. As shown in Fig. 1, the feed screw 12 terminates at the entrance to the retort and is confined almost wholly within the housing.

In order to secure uniform distribution of the incoming fuel to all parts of the retort, and also to secure agitation of the fire bed, the movable pusher bar 13 is given a reciprocating motion. The bar 13 with its members 14, while reciprocating, rakes the fuel to and fro while advancing it in the retort causing the same to be uniformly distributed throughout the length of the retort and over its fuel burning area, and prevents piling up of the fuel at different points longitudinally of the retort. Since members 14 extend upwardly from bar 13, the fire bed is agitated sufficiently to prevent caking of the fire bed. Bar 13 with its agitating or raking members 14, thus, in effect, functions as a sliding bottom.

The pusher bar 13 is reciprocated longitudinally of the retort by means of connecting rod 30 provided with a roller 31 which engages rotating cam 32. Cam 32 is fastened to power take-off shaft 33 and is rotated thereby and because of its contour produces a wobbling movement which causes roller 31 and with it rod 30, to reciprocate. Rod 30 is supported by bearings 34 and 35 and bar 13 is supported at its rearward end by bearing 36 and at its forward end by bearing 37.

Heretofore the fuel worked into the space between the bar and the bottom of the retort, according to the prior art, cumulatively packed there, and exerted an upward pressure on the bar. This pressure tended to lift the bar and to bend it upwardly and caused an upward pressure on the bearings for the bar thereby excessively increasing the wear on the bearings as well as increasing the friction and

power consumed for driving the stokers. In some cases this strain has broken shear bolts in the driving mechanism and has broken bearing supports.

In the preferred form of the invention, pusher bar 13 is somewhat triangular in transverse section within the limits of the retort with the apex of the triangle disposed lowermost, as shown in Fig. 2. This reduces the area under which fuel may pack. Also, preferably, at spaced intervals along said bar within the limits of the retort are triangular members 40 extending on both sides of the bar 13 which complete the bar to form a rectangular transverse section as shown in Fig. 2. The extensions 40, as shown in Fig. 4, are preferably provided with large fillets where they join the body portion of the bar. As bar 13 is reciprocated the extensions 40 act as plows, pushing the coal aside. By the combination of the plow extensions 40 and the small area of bar 13 which faces the bottom 41 of retort 10 the tendency for the coal to pack under the bar has been so minimized as to practically eliminate the difficulties heretofore experienced.

What I claim is:

1. In an underfeed stoker having a retort and means for delivering the fuel to the retort at one end thereof; a pusher bar in the retort having

a generally triangular transverse section within the limits of the retort with the apex disposed adjacent the bottom of the retort; and members extending on both sides of the bar at spaced intervals to form thereat generally rectangular transverse sections and large fillets between the extending members and the bar.

2. In an underfeed stoker having a retort and means for delivering the fuel to the retort to one end thereof; a pusher bar mounted adjacent the bottom of the retort for longitudinal reciprocation therein having a generally rectangular transverse section with concave indentations at spaced intervals extending into the lower portions of both sides and the bottom side of the bar.
